UNITED STATES PATENT OFFICE.

WILLIAM HAWKS, OF DULUTH, MINNESOTA, ASSIGNOR OF ONE-HALF TO CHARLES W. ANDREWS, OF DULUTH, MINNESOTA.

WATER-HEATING APPARATUS.

1,072,609.

Specification of Letters Patent.

Patented Sept. 9, 1913.

Application filed November 25, 1908. Serial No. 464,406.

To all whom it may concern:

Be it known that I, WILLIAM HAWKS, a citizen of the United States, residing at Duluth, in the county of St. Louis and State 5 of Minnesota, have invented certain new and useful Improvements in Water-Heating Apparatus, of which the following is a specification.

This invention relates to improvements in 10 water heating apparatus more particularly adapted for use with domestic stand boilers, and the primary object of the invention is to provide an improved form of heater in which the water will enter at a point lower 15 than the discharge outlet to induce circulation.

A further object is to provide improved means for arresting and deflecting the heat against the heater, and means for adjustably supporting the burner.

To the attainment of these ends and the accomplishment of other new and useful objects, as will appear, the invention consists in the features of novelty in the construction, combination and arrangement of the several parts hereinafter more fully described and claimed and shown in the accompanying drawings illustrating the embodiment of the invention, and in which—

30 Figure 1 is a longitudinal sectional view of an improved device of this character constructed in accordance with the principles of this invention. Fig. 2 is a detail sectional view on line 2—2 of Fig. 1. Fig. 3 is an 35 enlarged detail sectional view on line 3—3 of Fig. 4. Fig. 4 is a top plan view of the burner. Fig. 5 is an enlarged detail sectional view similar to Fig. 1 of a modified arrangement of the heater.

40 Referring more particularly to the drawings and in the present exemplification of the invention, the numeral 10 designates the ordinary stand boiler, which is provided with a supply inlet 11, connected to which 45 is a tubular member 12 which extends into the boiler at a point adjacent the bottom thereof, and 13 designates the outlet opening at the top of the boiler for conducting the heated water to the point of use.

50 Depending from the bottom 14 of the boiler, preferably at the center thereof, is a tubular member 15 which has communication with a heater designated generally by the reference numeral 16 in Figs. 1 and 55 5. This heater 16 may be constructed in any

desired or suitable manner but is preferably cast and is hollow to form a circumferential chamber 17 which has communication with a chamber 18, which is preferably located at the center of the heater by an upwardly inclined passage 19. A portion of the bottom of the chamber 17, preferably a portion located diametrically opposite to the passage 19, is depressed as at 20 and depending from the heater is a circumferential flange 60 or heat deflector 21 which surrounds the heater. 65

The extremity of the tubular member 15 which depends from the bottom 14 of the boiler 10 is connected to the heater 16 so as 70 to have communication with the chamber 18. A tubular member 22 is also provided to form a communication between the boiler 10 through the bottom 14 thereof at a point remote from the tubular member 15, and 75 this tubular member 22 extends into the heater 16 through the top thereof and into the depressed portion or chamber 20. The bottom of this depressed portion 20 is located at a point below the inlet end of the 80 passage 19 and the extremity of the tubular member 22 which projects into the depressed portion or chamber 20 terminates at a point below the bottom of the inlet or the 85 passage 19, so that the water from the boiler 10 will be discharged into the heater 16 through the tubular member 22 and into the depressed portion or chamber 20 so as to 90 enter the heater at a point below the entrance to the passage 19, thereby causing the water to circulate through the heater in an upward direction and out through the tubular member 15. 95

Arranged within the boiler 10 is a pipe or tubular member 23 which has communication with the tubular member 15 and extends to a point adjacent the top of the boiler so that the heated water entering the tubular member 23 will be conveyed to a point above the point at which the cold 100 water enters the boiler through the tubular member 12.

The heater 16 is supported by means of a stand 24 which is provided with a base 25, and this stand 24 is secured to the heater 105 16 in any desired or suitable manner, preferably by means of the threaded extremity 26 thereof engaging in a suitable threaded aperture in a reinforced portion 27 at the diametric center of the heater, and when 110

the heater is thus supported the boiler 10 will in turn be supported by the heater through the medium of the tubular member 15.

- 5 A shell or jacket 27 surrounds the boiler and is spaced therefrom. This shell or jacket is provided with an open lower extremity and depends below the bottom of the boiler 10 so as to surround the heater 16 and to project below the heater. The shell or jacket may be supported and held in position in any desired or suitable manner but is preferably supported by the heater 16 which latter may be provided with 10 a plurality of projecting peripheral lugs 28, 29, which engage the inner face thereof, and suitable fastening devices 30, such as screws or bolts, may be provided which pass through the shell or jacket and into 15 the lugs.
- 20 Arranged below the heater 16 is a burner designated generally by the reference numeral 31 in Figs. 1 and 5. This burner is adjustably supported on the stand 24 so as to be moved toward or away from the heater 16 and into and out of the lower extremity of the shell or jacket 27. A suitable fastening device 32^c, such as a screw or bolt, is provided for securing the burner in 25 its adjusted position.

30 The burner 31 preferably comprises a bottom ring-shaped member 32 which is of a channel formation, the outer flange 32^a of which is preferably inclined outwardly, and 35 an upper ring-shaped member 33 which is preferably convexed and is provided with a plurality of notches or open recesses 34 arranged around the periphery thereof. This member 33 of the burner is also provided with a depending flange 35 which is 40 adapted to surround the inner flange 32^b of the bottom member 32 and to rest upon the member 32 between the flanges when placed in position so that the notches or recesses 34 45 will stand adjacent the upper edge of the outer flange 32^a. The flange 35 of the member 33 is slightly spaced from the flange 32^b of the member 32 and is held spaced therefrom by means of a plurality of lugs 36 50 which project beyond the flange 35 and engage the adjacent face of the flange 32^b, as shown more clearly in Fig. 4 of the drawings. The notches or recesses 34 are so disposed that the flame therefrom will strike 55 or impinge the depending flange or heat deflector 21 of the heater 16, which latter will direct the flame against the bottom of the heater. By providing the lugs 36 on the member 33, a circumferential space 37 60 will be formed around the inner periphery of the burner, which space may be of any desired width but is preferably a narrow space through which gas will pass to be ignited and burned around the inner edge 65 of the ring. The purpose of this space and

the supplemental flame is to form a tight joint to prevent the escape of gas and thereby obviates the necessity of constructing a burner having fluid tight joints where the parts join. With this construction, the 70 burner may be constructed of two coöperating members, one of which removably rests upon the other member so that when it is desired to clean the burner, all that is necessary after the flame has been extinguished 75 is to release the fastening device 32^c and lower the burner 31 on the stand 24 away from the heater 16 to a convenient point for the operator, after which the member 33 may be lifted from the member 32 and access 80 will be had to the inside of the burner.

The burner may be supplied with fuel through a suitable supply pipe 38 having a nozzle 39 which discharges into a tubular extension 40 of the burner. 85

In order to permit the burner to be readily lowered so as not to engage the nozzle 39 of the supply pipe 38, all that is necessary after releasing the fastening device 32 is to raise the burner slightly on 90 the stand 24, after which it may be axially rotated to move the tubular extension out of line with the nozzle 39 after which the burner may be readily lowered.

The heater 16 is provided with openings 95 41 between the circumferential chamber 17 and the chamber 18, and which openings are located below the bottom of the boiler 14 so that the products of combustion from the burner will pass through the openings and 100 impinge upon the bottom 14 of the boiler; at the same time the products will escape into the space between the boiler and the shell or jacket 27, which latter may be provided with a vent opening 42 at the top 105 thereof for the escape of the products.

The heater 16 is provided with an upwardly projecting circumferential flange 43 extending above the top thereof to form a receptacle to catch the products of condensation which may be formed upon the surface of the boiler. The heater may also be provided with openings 44 which extend through the periphery thereof, preferably 110 through the lugs 29, and said openings have 115 communication with the chamber 17 so that when it is desired, an inlet pipe 45 which leads from the water-back of the furnace may be connected to one of the openings to have communication with the chamber 17, 120 and the outlet pipe 46 leading to the water-back may be connected to the other opening 44 so that in the event that the water-back of a furnace is attached to a heater, the water entering the heater 16 through the tubular member 22 will pass out of the heater through the pipe 46 and into the water-back. From the water-back it will pass 125 through the pipe 45 to be discharged into the heater 16 to flow through the passage 19, 130

chamber 18, tubular member 15, pipe 23, and back into the boiler.

When it is not desired to use the water-back, the pipes 45 and 46 may be detached 5 from the heater 16 and suitable plugs 47 may be inserted in the openings 44 to close the same, the shell or jacket 27 being provided with apertures registering with the openings 44 to permit the attachment of the 10 pipes or plugs 47.

With this improved construction it will be apparent that by providing the depending flange 21 on the heater, the flame from the burner will be gathered in such a manner 15 as to deflect the same toward the center of the heater and through the openings 41 against the bottom of the boiler. It will also be apparent that by providing the catch basin or receptacle at the top of the heater 20 for the water of condensation which forms when the boiler is first heated, the water will be allowed to accumulate therein and when the heater becomes sufficiently hot, the water 25 of condensation will be converted into vapor and carried off through the vent opening 42.

In order that the invention might be fully understood the details of the foregoing embodiment thereof have been thus specifically 30 described, but

What is claimed as new is—

1. A water heater comprising a body having an annular water chamber and an outlet chamber encompassed by the annular chamber, the bottom of the second recited chamber being located in a plane above the bottom of the annular chamber, an inlet passage 35 for the inner chamber leading from the annular chamber and inclining upwardly therefrom, an outlet for the inner chamber leading through the top thereof and an inlet opening for the annular chamber, the bottom of the latter chamber adjacent the inlet opening being depressed.

45 2. A water heater comprising a body having an annular water chamber and an outlet chamber encompassed by the annular chamber, the bottom of the second recited chamber being located in a plane above the bottom 50 of the annular chamber, an inlet passage for the inner chamber leading from the annular chamber and inclining upwardly

therefrom, an outlet for the inner chamber leading through the top thereof and an inlet opening for the annular chamber, the bottom of the latter chamber adjacent the inlet opening being depressed, said chambers being spaced from each other to form a heat 55 passage therebetween.

3. A water heater comprising a body having an annular water chamber and an outlet chamber encompassed by the annular chamber, the bottom of the second recited chamber being located in a plane above the bottom of the annular chamber, an inlet passage 60 for the inner chamber leading from the annular chamber and inclining upwardly therefrom, an outlet for the inner chamber leading through the top thereof and an inlet opening for the annular chamber, the bottom of the latter chamber adjacent the inlet opening being depressed, said chambers being spaced from each other to form a heat 65 passage therebetween, and said heater being provided with integral wall at the top thereof to form an upwardly opening receptacle 70 for the water of condensation.

4. A water heater comprising a body having an annular water chamber and an outlet chamber encompassed by the annular chamber, the bottom of the second recited chamber being located in a plane above the bottom of the annular chamber, an inlet passage for the inner chamber leading from the annular chamber and inclining upwardly 80 therefrom, an outlet for the inner chamber leading through the top thereof and an inlet opening for the annular chamber, the bottom of the latter chamber adjacent the inlet opening being depressed, said chambers being spaced from each other to form a heat 85 passage therebetween, the outer chamber being provided with an integral depending annular flange encompassing the inlet to the said heat passage.

In testimony whereof I have signed my name to this specification, in the presence of two subscribing witnesses, on this 20th day of November A. D. 1908.

WILLIAM HAWKS.
